FLOW CONTROL MECHANISM FOR
COOLING SYSTEMS

Robert H. Goddard, deceased, late of Annapolis, Md., by Esther C. Goddard, executrix, Worcester, Mass., assignor of one-half to The Daniel and Florence Guggenheim Foundation, New York, N. Y., a corporation of New York

Application June 25, 1947, Serial No. 756,863

4 Claims. (Cl. 257—2)

1

This invention relates to cooling systems and particularly to cooling systems associated with the jacketing of combustion chambers and discharge nozzles in propulsion apparatus.

It is the general object of this invention to improve the efficiency of such cooling mechanism by varying the flow of cooling liquid inversely to the resistance to flow of said liquid.

A further object is to provide mechanism for separately controlling the flow in each channel of a subdivided jacket space and inversely to the resistance to flow in each channel.

The invention further relates to arrangements and combinations of parts which will be herein-after described and more particularly pointed out in the appended claims.

A preferred form of the invention is shown in the drawings, in which

Fig. 1 is a perspective view of a portion of a jacketed discharge nozzle embodying this invention;

Fig. 2 is a projected view illustrating the operation of the regulating vanes;

Fig. 3 is a side elevation, partly in section, showing one regulating vane and its supporting and control devices; and

Fig. 4 is a side elevation, looking in the direction of the arrow 4 in Fig. 3.

Referring to the drawings, a portion of a conical discharge nozzle 10 is shown as provided with an outer casing 11 and with a plurality of longitudinally extended radial vanes 12, which together define a jacket space subdivided into channels 14. The lower end of each channel has an unobstructed entrance from a manifold or volute 20 supplied with a cooling fluid through a feed pipe 21. The lower end of each vane 12 is curved, as indicated at 12a, to direct a portion of the cooling liquid into the associated channel 14, through which channel the liquid flows upwardly.

In the upward travel of the cooling liquid, portions of the liquid may be vaporized by contact with the hot surface of the nozzle 10. This vapor may then accumulate in one or more channels, thus causing gas bind and restricting the flow of the cooling liquid therethrough. As the vapor itself is a very poor heat conductor, the associated nozzle wall portions may be quickly injured by overheating.

In order to correct this undesirable condition, a vane 30 is mounted at the lower end or entrance of each of the channels 14. Each vane 30 is loose on an arm 31 of an arbor 32 (Fig. 2) supported in bearings in a casing 33 extending outward from the jacket casing 11. A coil spring 35 is enclosed

2

in the casing 33 and tends to move the vane 30 clockwise as viewed in Fig. 4 or from the position shown at 30a in Fig. 2 to the position shown at 30b. The upper end portion of each vane is more sharply curved.

As water flows around the volute 20, it engages the lower portion of each vane 30 and a portion is diverted into each channel 14. As the water flows upward in each channel, the action of the water against the vane tends to swing each vane from its lower toward its raised position, and in its raised position reduces the flow of water to the amount required for cooling under normal conditions.

15 In case of gas bind, the flow of water in a particular channel is restricted, so that there is less force to hold the vane in raised position. The associated spring 35 then moves the vane downward toward its lower position, thus directing 20 more water into the channel. This increased flow produces additional cooling effect in the channel in which flow was restricted by gas bind and quickly clears the accumulated vapor out of the channel. Further increased flow then raises the 25 vane again to normal operating position.

Accordingly, this invention discloses mechanism well adapted to regulate the flow of cooling liquid in any channel inversely to the restriction of liquid flow in such channel.

30 Having thus described the invention and the advantages thereof, it will be understood that the invention is not to be limited to the details herein disclosed, otherwise than as set forth in the claims, but what is claimed is:

35 1. In a cooling system, a jacket having a plurality of adjacent passages for cooling liquid, a common liquid supply for all of said passages, a liquid-diverting device in each of said passages which is movable out of liquid-diverting position in said 40 common supply by engagement with a normal flow of liquid in the associated passage, and spring means to advance each device to diverting position with respect to said common supply when flow through the associated passage is retarded 45 and reduced.

2. In a cooling system, a branch passage, a liquid supply therefor, a vane in said branch passage having a diverting portion movable into said liquid supply, and a spring to move said vane into said passage, said vane having a portion engaged by liquid flowing through said passage and said vane being moved out of said supply when thus engaged by a normal flow of liquid.

3. In a cooling system, a liquid supply passage, 55 a branch passage, a diverting vane pivoted at the

entrance of said branch passage and having a portion movable into said supply passage and having another portion engaged by liquid flowing through said branch passage, such engagement by a normal flow of liquid being effective to withdraw said vane from said supply passage, and a spring to move said vane toward diverting position.

4. In a cooling system, a jacket having a plurality of adjacent passages for cooling liquid, a common liquid supply for all of said passages, a liquid diverting device pivoted in each of said passages, and spring means to swing each device to diverting position with respect to said common supply, and each device being moved from divert-

10
15

ing position by engagement with normal flow of liquid through its associated passage.

ESTHER C. GODDARD,
*Executrix of the Last Will and Testament of
Robert H. Goddard, Deceased.*
